CLAIM

The ornamental design for a stand for display screen as shown and described.

DESCRIPTION

1.1 : Front Perspective view of a stand for display screen in a first position

1.2 : Rear perspective view thereof

1.3 : Front elevation view thereof

1.4 : Rear elevation view thereof

1.5 : Left elevation view thereof, the right elevation view is a mirror image thereof

1.6 : Top plan view thereof

1.7 : Bottom plan view thereof

1.8 : Enlarged view taken from **1.2**

1.9 : Rear perspective view thereof shown with additional environment

1.10 : Rear perspective view thereof shown with a broken line screen environment in a state of use

1.11 : Rear perspective in a second position

1.12 : Left view thereof, the right is a mirror image thereof

1.13 : Left view in a third position, the right is a mirror image thereof

1.14 : Top plan view thereof

(Continued)

The evenly spaced broken lines immediately adjacent to the claim depict the bounds of the claimed design, while all other evenly spaced broken lines are directed to environment. The dot-dash line and adjoining curvy line illustrate the bounds of the enlarged view and form no part of the claimed design. The broken lines form no part of the claimed design.

The stand for display screen includes structures with transparent surfaces.
